UNITED STATES PATENT OFFICE.

HARRY A. LAHMAN, OF KANSAS CITY, KANSAS.

DESIGN FOR A FLOWER HOLDER.

Application filed May 27, 1927. Serial No. 22,206. Term of patent 3½ years.

To all whom it may concern:

Be it known that I, HARRY A. LAHMAN, a citizen of the United States, residing at Kansas City, in the county of Wyandotte and State of Kansas, have invented a new, original, and ornamental Design for a Flower Holder, of which the following is a complete specification, reference being had to the accompanying drawing, forming a part thereof.

Fig. 2, is a front elevation of the same.

I claim:

The ornamental design for a flower holder as shown.

HARRY A. LAHMAN.
